HAIR CLIPPER COMB PLATE ATTACHMENT

Mathew Andis, Racine, Wis., assignor to Andis Clipper
Co., Racine, Wis., a corporation of Wisconsin

Application April 19, 1954, Serial No. 30,058

Term of patent 14 years

(Cl. D22—5)

Fig. 1

Fig. 2

Fig. 3

Fig. 4

Fig. 5

Fig. 6

Fig. 7

Fig. 8

Fig. 1 is a front perspective view of a hair clipper comb plate attachment showing my new design.

Fig. 2 is a rear perspective view thereof.

Fig. 3 is a front elevational view.

Fig. 4 is a right side elevational view.

Fig. 5 is a rear elevational view.

Fig. 6 is a bottom edge view of the device as shown in Fig. 3.

Fig. 7 is a cross sectional view thereof taken on line 7-7 of Fig. 3.

Fig. 8 is a cross-sectional view thereof taken on line 8-8 of Fig. 3.

I claim:

The ornamental design for a hair clipper comb plate attachment, substantially as shown.
